CLAIM

The ornamental design for a workstation as shown and described.

DESCRIPTION

FIG. 1 is an upper, left, front perspective view of my new design for a workstation.

FIG. 2 is an upper, left, rear perspective view thereof.

FIG. 3 is a front elevation view thereof.

FIG. 4 is a rear elevation view thereof.

FIG. 5 is a right elevation view thereof.

FIG. 6 is a left elevation view thereof.

FIG. 7 is a top plan view thereof.

FIG. 8 is a bottom plan view thereof; and,

FIG. 9 is another upper, left, front perspective view thereof. The broken lines shown in the figures depict portions of the workstation that form no part of the claimed design. The shade lines shown represent surface shading and not surface ornamentation or material type.
